LAMINATED HEAT EXCHANGER

Sven Holm and William E. Hammond, Wellsville,
N. Y., assignors to The Air Preheater Corpora-
tion, New York, N. Y.

Application July 24, 1948, Serial No. 40,546

4 Claims. (Cl. 257—245)

1

The present invention relates to improvements in heat exchangers of the plate type particularly adapted for heat exchange between two confined fluids.

The invention contemplates the construction of a plate type heat exchanger by stacking blanks that are formed with a plurality of variously arranged perforations in the form of rows of apertures or slots co-extensive with the rows, the assembly of the blanks aligning the perforations to form fluid passages and portions of certain plates forming extended surfaces or fins in the passages created by the alignment of apertures and/or slots in the plates. The invention will best be understood upon consideration of the following detailed description of illustrative embodiments thereof when read in conjunction with the accompanying drawings in which:

Figure 1 is a perspective view of an envelope type heat exchanger embodying the present invention, parts being broken away to illustrate details of construction.

Figures 2 to 5, 5A, 6 and 6A are perspective views illustrating perforated plates of various forms which may be assembled in combinations to form the core of the heat exchanger illustrated in Figure 1;

Figure 7 is a fragmentary perspective view of a core made up of alternate "A" plates having rows of apertures and intermediate "B" plates having slots as shown in Figures 2 and 3, respectively;

Figure 7A is an exploded perspective view corresponding to Figure 7.

Figure 8 is an end elevational view, partly sectioned, and Figure 9 is a horizontal sectional view on the correspondingly designated section line in Figure 7.

Figure 10 is a view similar to Figure 9 but having the pin-fins in the core disposed in staggered relation.

Figure 11 also is a sectional view similar to Figure 9 but wherein all of the component plates of the core are of the "A" type having rows of apertures as illustrated in Figure 2, thereby providing continuous fins extending through the passages in the direction of fluid flow.

Figure 12 is a sectional view similar to Figure 11 but having the continuous longitudinal fins interrupted at intervals by periodic insertion of slotted plates of the "B" type shown in Figure 3 between groups of row apertured plates of the "A" type shown in Figure 2.

Figure 13 also is a sectional view of a portion of a core made up of row apertured "A" plates

2

of the type shown in Figure 2 used in alternation with plates of the "C" type shown in Figure 4 which have slots as well as rows of apertures so that some passages have a plurality of pin-fins therein while other contiguous passages have continuous longitudinal fins extending through the passages in the direction of fluid flow.

Figure 14 is a sectional view showing a core similar to that in Figure 13 but having slotted "B" plates of the form shown in Figure 3 interposed at intervals to interrupt the continuity of the longitudinal fins.

Figure 15 is a fragmentary perspective view of a core utilizing in alternation "A" and "D" plates of the forms shown in Figures 2 and 5 so arranged as to provide for cross flow of the two fluids.

Figure 15A is a view similar to Figure 15 employing a variant of the "D" plates with the "A" plates.

Figure 16 is a partial sectional view of a core of the type shown in Figure 15.

The heat exchanger illustrated in Figure 1 is essentially of the envelope type with alternating passages for two fluids in heat exchange relationship and has a core 10 consisting of a plurality of stacked blanks or plates 11, 12 formed with perforations that create passages for counterflow of two fluids in heat exchange relationship. The fluid to be heated passes from a header 13 through the manifold fingers 14 to alternate passages in the heat exchanger core 10 and is discharged in like manner from the outlet ends of the passages through similar fingers to a collecting header 15. At the same time the heating fluid is supplied through a header 16 to flow through the manifold fingers 17 into the set of intermediate passages and is taken off through other manifold fingers which communicate with the discharge header 18.

One of the primary components of the core 10 is the heat exchanger plate 11 shown in Figure 2, also to be referred to as an "A" plate. The plate 11, preferably of thin, highly heat-conductive metal or other material, is formed with a plurality of perforations which, as shown, are arranged in alignment transversely of the plate to form a series of transverse rows 20 of apertures 21. Other plates 12 shown in Figure 3 known also as "B" plates have transversely extending slots 22 co-extensive with the transverse rows 20 of apertures 21 in the plates 11 and the slots 22 are spaced to correspond with the vertical spacing of the rows 20 of apertures 21. When a number of these "A" plates 11 are stacked

(Fig. 7) in alternation with "B" plates 12 the apertures 21 form continuations of the slots 22 to create continuous fluid passages extending through the core (Fig. 8). The ligaments 24 between the adjacent apertures 21 in the plates 11 constitute pin-like fins 30 (Figs. 7 and 9) extending across the flow passages from the passage walls which are themselves constituted by the transverse ligaments 25 between the rows 20 of apertures 21 in the "A" plates and the similar ligaments 26 between the slots 22 of the "B" plates. The apertures 21 and ligament-fins 24 may be .040 of an inch wide or greater and say .25 of an inch high. The pin-fins 30 occur in the heat exchange core 10 at spaced intervals corresponding to the thickness of the "B" plates and themselves are of a depth or thickness corresponding to that of the "A" plates from which they are formed or in the nature of .040 inch.

If the apertures in adjacent rows are staggered, the pin-fins 30 in adjacent passages also become staggered. By employing "A" plates in which the rows 20 of the apertures 21 begin at different distances from the side edge of the plates than shown for the rows of apertures in Figure 2, the pin-fins in the passages of the core may be staggered. This may be brought about also as shown in Figure 10 by employing plates which have a wider margin 21 at one side than at the other and reversing alternate "A" plates to dispose the wider margin alternately at the right or left hand side of the core.

When it is desired to provide a continuous fin structure extending entirely through the core in the direction of fluid flow the entire core is then made up of "A" plates, the ligaments 24 of the adjacent plates abutting as well as aligning to form continuous webs or ribs 29 between the passages formed by the alignment of the apertures 21 (Fig. 11).

When it is desired to interrupt the continuous fins formed by abutting the ligaments 24 of a plurality of stacked "A" plates, a "B" plate is inserted at each point where it is desired to interrupt the fins (Fig. 12), this occurring because the "B" plates being formed with full transverse slots 22 do not have the ligaments 24 that separate the apertures 21 in an "A" plate.

To create a core having pin-like fins 30 in one set of passages with continuous fins through the adjacent passages, "A" plates having rows of apertures 21 are combined with "C" plates 31 (Fig. 4) of a type having alternate slots 22 and rows of apertures 21. By assembling "A" plates in alternation with the "C" plates one set of passages will have pin fins 30 spaced in the direction of flow while the set of intermediate passages will be provided with continuous fins formed by the ligaments 33 between the openings 34 abutting with the aligned ligaments 24 of the "A" plates as shown in Fig. 13. Insertion at intervals in the core of "B" plates serves to interrupt the continuity of the fins (Fig. 14).

Although shown as being of rectangular form the plates 11, 12 etc. may be circular, oval, annular or of any other shape considered suitable for a particular heat exchanger use. With the arrangements described above, the rows of apertures 21 in a set of "A" plates combine with the slots 22 in the sets of "B" or "C" plates to create passages extending through the heat exchange core, the passages being separated by walls made up of the ligaments 25, between rows 20 of apertures or the ligaments 26 between slots 22 while the ligaments 24 between the apertures 21 form

spaced pin-fins when "A" plates formed only with apertures are stacked alternately with "B" plates 12 formed only with slots, while a "C" plate formed with both types of openings when combined with "A" plates formed only with rows of apertures 21 creates spaced pin-fins in one set of passages and longitudinally extending fins in the adjacent passages.

To create manifolds at either end of the heat exchange core 10 (Fig. 1) a number of slotted "B" plates (Fig. 3) are stacked upon and below the heat exchange core so that the fingers 14, 17 of headers 13, 15, 16, 18 may be inserted in the wells or recesses formed by the slots 22 in the several plates 12 at each end of core 10.

Where cross-flow is desired, instead of the "B" plates of Fig. 3, plates 60 of the form shown in Fig. 5 are employed with the "A" plates. It will be noted that in the "D" plates 60 alternate slots 61 are longer than the other slots 62. The slots 61 are wider than the rows of apertures 21 in the "A" plates and the "D" plates themselves are proportionately wider. When "D" plates of this form are used in alternation with "A" plates with the shorter slots 62 in the "D" plates aligned with the rows of openings 21 in the "A" plates so as to be co-extensive therewith, the side portions of the plates 60 are cut off in planes "X" located at the positions beyond the ends of slots 62 and passing through the intermediate long slots 61 near their ends. This opens up the ends of these slots to form passages for fluid to flow through them in a direction from the side edges of the plates (Fig. 15). With this form special end plates 63 of the type shown in Fig. 6 and known as "E" plates are employed which have slots 64 to communicate with the passages formed by the slots 62 etc. while imperforate portions 65 of the "E" plates are wide enough to close the sides of the passages created by the slots 61 that open to that face of the core.

Figure 15A shows an arrangement similar to that of Figure 15 but the plates 66 (called D' plates) have rows of apertures 67 instead of short slots 62 of the D' plates. When assembled with A plates continuous fins are formed in one set of passages.

What we claim is:

1. A heat exchanger comprising: a core made up of stacked plates formed with spaced parallel rows of apertures separated at intervals by plates formed with similarly spaced, parallel slots with the apertures and slots aligned to form parts of parallel passages and the ligaments between contiguous apertures in said rows constituting fins that occur in the passages at intervals in the direction of flow corresponding to the thickness of said slotted plates; a plurality of plates disposed at each end of the core formed with slots spaced to correspond with the spacing of said passages and constituting extensions thereof; a pair of manifolds disposed at opposite ends of the core having finger-like conduits extending into alternate slots in said end plates for admitting fluid to and receiving it from the passages of said core; and other similar manifolds having fingers connecting with the intermediate slots in said end plates for circulating another fluid through intermediate passages.

2. A heat exchanger comprising: a core made up of stacked plates formed with spaced parallel rows of apertures with the apertures of contiguous plates aligned to form parts of parallel passages and the ligaments between contiguous apertures in said rows constituting fins in the passages

in the direction of flow; a plurality of plates disposed at each end of the core formed with slots spaced to correspond with the spacing of said passages and constituting extensions thereof; a pair of manifolds disposed at opposite ends of the core having finger-like conduits extending into alternate slots in said end plates for admitting fluid to and receiving it from the passages of said core; and other similar manifolds having fingers connecting with the intermediate slots in said end plates for circulating another fluid through intermediate passages.

3. A core for a heat exchanger comprising a plurality of stacked plates all of good heat transferring material, each formed with a multiplicity of non-circular, elongate spaced perforations arranged in substantially uniform patterns to occupy corresponding areas on the various plates, said perforations aligning from plate to plate to form parts of parallel fluid passages through the core; sections of the plate members which lie between perforations forming ligaments adapted to abut to constitute fins extending through said passages in the direction of fluid flow; plates having parallel rows of slots of a length corresponding to said rows of perforations so that pin-like fins occur in the passages at intervals in the direction of flow corresponding to the thickness of the slotted plates, said perforations being located at different distances from the marginal edges of the plates so that fins formed by ligaments between perforations are offset transversely of said passageways.

4. A core for a heat exchanger comprising: a plurality of stacked plates of heat exchanger ma-

10

15

20

30

35

terial formed with a multiplicity of apertures arranged in parallel rows; other plates disposed among said first plates and formed with slots co-extensive with and spaced at intervals corresponding to the spacing of the rows of apertures in said first plates for alignment therewith, whereby the ligaments on the plates between said rows of apertures and said rows of slots constitute opposite walls of fluid passages extending through the core, and the ligaments between the apertures in said rows constitute pin-like fin extensions from said walls into said passages; the initial aperture in each row of apertured plates being located at different distances from the marginal edges of the plates than the final aperture, and alternate apertured plates being reversed so that the said fins formed by ligaments of contiguous apertured plates are staggered in said passages.

SVEN HOLM.
